TOOL FOR WINDING WIRES ONTO TERMINALS
Jacob C. Bach, La Grange, William F. Fivek, Berwyn,
and Robert A. Heyden, Palos Heights, Ill., assignors to
Western Electric Company, Incorporated, a corpora-
tion of New York

Filed June 17, 1960, Ser. No. 36,808
2 Claims. (Cl. 242—7)

The present invention relates to tools for winding wires onto terminals, and more particularly to wire winding tools having spring loaded rotary bits for preventing overwrapping of the wire.

Heretofore in portable wire winding tools for wrapping wire onto terminals the rotatable wire winding bit of such a tool was held against axial movement relative to the tool housing so that the tool would have to be withdrawn by the operator in synchronism with the winding of the wire onto the terminal in order to obtain a single layer of winding on the terminal and prevent the overwrapping of the wire thereon. In the event that the operator should retract the wire winding tool at a slower pace than the wire was being wound onto the terminal, the wire would overwrap a portion of the first layer thereof and produce an undesirable connection with the terminal.

An object of the present invention is to provide an improved tool for winding wires onto terminals.

Another object of the invention is to provide a wire winding tool having a spring loaded wire winding bit for preventing the overwrapping of a wire being wound onto a terminal.

With these and other objects in mind, the invention contemplates the provision of a portable wire winding tool having a rotatable motor-driven driving member provided with a recess for receiving the end of a wire winding bit. The bit is rotatably mounted in the housing of the tool for limited axial movement and is connected to the bit-driving member for rotation therewith and for axial movement relative thereto, and the bit is urged axially by a spring to a normal forward position so that in the event the wire winding tool is not retracted by the operator as rapidly as the wire is being wound onto the terminal during a wire winding operation, the bit will be moved axially relative to the tool housing by the wire being wound onto the terminal and thus prevent overwrapping of the wire.

Other objects, advantages and novel aspects of the invention will become apparent upon consideration of the following detailed description, in conjunction with the accompanying drawings wherein:

FIG. 1 is a longitudinal sectional elevational view of a wire winding tool embodying the present invention;

FIG. 2 is a cross sectional view of the wire winding tool taken on line 2—2 of FIG. 1;

FIG. 3 is a fragmentary view of several of the components of the tool in separated relation to each other; and

FIG. 4 is a view of a wire wound onto a terminal with the present tool.

Referring to FIG. 1 of the drawings, the wire winding tool 10 comprises a housing 12 enclosing an air-driven motor 14 and having a handle 16 by means of which the tool may be gripped by an operator. Compressed air is supplied to the air motor through a flexible tube 17 and the motor is operated under control of a trigger 18. The air motor is connected to and rotates a driving or bit receiving member 20 which is supported in a composite hollow nose section 22 extending forwardly from the housing 12 and secured thereto by a nut 23. At its forward end the driving member 20 is provided with an axially disposed cylindrical recess 24 for receiving one

2

end 26 of a one-piece replaceable wire winding bit 28. The bit 28 is rotatably supported in a tubular member 30 which extends forwardly from the nose section 22 and is supported in a split chuck 31. The chuck 31 is pressed into the end of the nose section 22 and has a nut 32 which may be turned for clamping or releasing the tubular member 30.

At its forward end the bit 28 is provided with an axially disposed recess 34 and a longitudinally disposed peripheral groove 36 which serve respectively to receive a terminal 38 and a wire 39 preparatory to the winding of the wire onto the terminal.

The other end 26 of the bit is rabbeted at 42 to provide a flat portion 43 which cooperates with a pin 44 in the driving member 20 to effect a driving connection between the driving member 20 and the bit 28 for imparting rotation to the bit while permitting axial movement of the bit relative to the driving member. A circular plug 45 is slidably mounted in the cylindrical recess 24 in engagement with the end of the winding bit 28, and a spring 46 interposed between the plug 45 and the end of the recess 24 serves to urge the plug and the bit 28 axially outwardly.

The inner end of the tubular member 30 engages a shoulder 48 formed on the enlarged end 26 of the bit 28 and serves to stop the bit in a normal operative position shown in FIG. 1. By loosening the chuck nut 32 and withdrawing the tubular member 30 the bit 28 may be removed and replaced.

From the foregoing it will be evident that the winding bit 28 is yieldably maintained in its normal operative position and is capable of being moved axially by the wire 39 being wound onto the terminal 38 to prevent overwrapping of the wire if the wire winding tool 10 is not withdrawn or is withdrawn too slowly from the terminal during the wire winding operation.

In the operation of winding a wire 39 around a terminal 38, the bared wire 39 of an insulated conductor is inserted into the longitudinal groove 36 in the bit 28 and bent laterally into a notch 52 in the end of the tubular member 30 after which the wire winding tool is moved relative to the terminal to effect the insertion of the terminal 38 into the recess 34 of the bit. The operator then depresses the trigger 18 to effect the operation of the air motor and the rotation of the bit 28. As the bit 28 winds the wire 39 onto the terminal 38, the operator normally withdraws the tool 10 in timed relation thereto. In the event that the operator fails to withdraw the wire-winding tool 10 rearwardly as fast as the wire 39 is being wound onto the terminal, the wire 39, as it is being wound, will apply a force to the bit 28 in an axial direction and impart axial movement thereto serving to compress the spring 46 and permit the completion of the winding of the wire in a single layer and thus prevent the overwrapping of portions of the wire 39.

It is to be understood that the above-described arrangements are simply illustrative of the application of the principles of this invention. Numerous other arrangements may be readily devised by those skilled in the art which will embody the principles of the invention and fall within the spirit and scope thereof.

What is claimed is:

1. A wire winding tool comprising a wire winding bit having a laterally projecting shoulder, a bit driving member, means interconnecting said wire winding bit and said bit driving member for rotational and axial movement of said bit, means for driving said bit driving member, a housing for supporting said driving means and said bit driving member for rotational movement, means removably attached to said housing for supporting said bit for rotational movement and for engaging said shoulder to

limit axial movement in a direction away from said bit driving member, and spring means interposed between said bit and said bit driving member for axially moving said bit into engagement with said shoulder.

2. A tool for winding a wire onto a terminal, comprising a housing including a tube removably secured to the housing and forming a portion thereof, a driving member supported on said housing for rotation about the axis of said tube and against axial movement and having an axially directed cylindrical recess closed at one end, means on said housing for rotating said driving member, a wire winding bit supported in said tube for rotation and for axial movement, said bit having a head at one end thereof slidably axially in said recess in said driving member and provided with a shoulder engageable with one end of said tube for limiting the axial movement of said bit away from said driving member to a normal operative position, a helical compression spring in the closed end portion of said recess of said driving member, a cylindrical plug slidable in said recess between and in

5 10 15 20

engagement with said spring and said head of said bit, said head of said bit having a rabbeted end portion adjacent to said plug, and a pin on said driving member extending through said recess in a plane perpendicular to the axis of said tool and cooperable with said rabbeted end portion of said bit for effecting a rotary drive connection between said driving member and said bit while permitting axial movement of said bit, the other end of said bit being provided with an axial recess and an eccentric longitudinally disposed recess for receiving a terminal and a wire respectively.
